UNITED STATES PATENT OFFICE.

JEAN H. KNOX, OF OAKLAND, CALIFORNIA.

CONCRETE CONSTRUCTION.

1,142,259.

Specification of Letters Patent.

Patented June 8, 1915.

Application filed June 11, 1913. Serial No. 772,968.

To all whom it may concern:

Be it known that I, JEAN H. KNOX, citizen of the United States, residing at Oakland, in the county of Alameda and State of California, have invented certain new and useful Improvements in Concrete Construction, of which the following is a specification.

This invention relates to a method of concrete construction, and particularly to the construction of bridge and pier members, the principal object of the invention being to provide a form for the reception of the concrete which is noncentering, needs no supporting falsework and which may be taken down and used over again any number of times.

Another object is to provide such a form which will both determine the shape of the concrete poured therein and support the same while setting.

A third object is to provide such a means as can be easily and quickly set up and taken down.

A fourth object is the elimination of accidents occasioned by use of the unstable falsework as at present employed.

These and other objects I accomplish by means of the particular arrangement and adaptation of parts as hereinafter described, and shown in the accompanying drawings, in which:

Figure 1 is a perspective view of a set of my improved concrete forms as set up for use. Fig. 2 is a side elevation partly broken out, of one of the arch members. Fig. 3 is an enlarged cross section on a line 3-3 of Fig. 2.

On the drawings, similar characters of reference indicate corresponding parts in the several views.

Referring now more particularly to the drawings, and to the figures of reference marked thereon, 1 represents the piers or abutments of the bridge or other design under construction. These piers are set up by any desired method, and are then coupled in pairs by means of hoops or bands 2 placed over the top of same, having tension rods 3 connected therewith, these rods being in turn connected by a turnbuckle 4 by means of which the tension may be regulated.

On top of these piers and seating thereon are members 5, which are made up of two V-shaped plates 6 the width of the pier, fastened together and across the pier by

angle irons 7, the bottom ones of which form a flange or seat for the piers 1. These angles are riveted on so that they will present a face all around to abut against the adjacent members 8, the top and bottom edges of which are curved to conform to the radius of the arch to be constructed. These members 8 and their adjacent members 9 are formed of bottom and side plates 10 and 11 of the respectively required sizes, and are also connected together and braced by angle irons 12, the faces of which along the edges of the ends are adapted to engage with the corresponding faces of the angles 7 of the members 5 and the corresponding faces of the angle irons 12 of members 9. These angle irons are drilled at intervals to admit of bolts 13 being used to couple the different members together when it is desired to set the arch up.

A portion 11^a of the adjacent side plates 11 of the members 8 of two arches is removed, and a trough 14 to connect two adjacent openings is formed in a manner similar to members 8 and 9—i. e., side and bottom plates 15, and reinforcing and connecting angle-irons 16, the end ones of which are adapted to be removably bolted to the members 8 of both arches. The length of these trough members 14 is of course determined by the distance apart of the piers 1.

It will be noticed that the V-shaped members 5 are isosceles triangles, having the connecting angles 7 on both sides thereof, thus rendering the same reversible, and if convenient and desired additional members 8 and 9 may be set up on the present disconnected side of members 5 to form more arches.

It will also be obvious that the portion 11^a may be cut out of side plates 11 on both sides thereof and at any points desired, and that there may be any number of the sections 9, should the length of the arch to be constructed or other reason render such necessary.

In operation, the form as a unit is set up as shown—or with additional arches as stated—and the concrete poured in from the top. This fills up the space between the plates of the arches and also the troughs 14. When the concrete has set, the various sections of the form are unbolted and each one taken down. There will then be set up integral with the piers 1, and with each other, suitable arch ribs and connecting brace

beams. The bands and rods 2—3 are for the purpose of preventing any possible spread of the piers while the weight of the forms and concrete is on them, before the setting 5 of the latter.

Thus it will be seen that I have perfected such a device as substantially fulfills the objects of the invention as set forth herein.

While I have here described and shown 10 the present and preferred embodiment of my invention, still in practice such deviations from such detail may be made as do not depart from the spirit of the invention.

I claim:

- 15 1. A mold adapted to form a unitary monolithic structure, comprising a plurality of sections adapted to form an arch form, angle irons adjacent the junctures of said sections, and obliquely disposed thereon, being adapted to unite and reinforce adjacent sections, piers supporting said molds, seat sections intermediate said piers and arch sections, said sections adapted to form a continuous U-shaped trough, and means secured to said piers, adapted to retain the mold in adjusted position, substantially as described.
- 20
- 25

2. A form for concrete arch construction, comprising a pair of arch forms, each of which is built up of a plurality of sections, 30 each of said sections having side and bottom plates, said side plates being spaced apart the width of the arch rib required, the same being reinforced at their junctures by suitably disposed angle-irons, the flanges of the 35 angle irons which lie along the bottom and side edges of any one section abutting against the corresponding flanges of the angles of the adjacent sections, means for connecting said flanges together, and open-top trough members connecting said two arch-forms from any two coinciding sections of each arch form, the said troughs opening into the interior of each arch-form and being removably connected therewith 40 whereby brace beams will be formed integral with the concrete arch-ribs as set forth.

In testimony whereof I affix my signature in presence of two witnesses.

JEAN H. KNOX.
